CAKE HOLDER FOR DYEING APPARATUS

Michael W. Reno and James E. Dougherty,
Philadelphia, Pa.

Application July 20, 1949, Serial No. 105,872

6 Claims. (Cl. 68—198)

1

This invention has general reference to holders for use in the treatment of yarns or threads in annular package or cake formation and, more particularly, relates to holders adapted to support a pile of packages or cakes during dyeing or other treatment with liquids. Holders of the type referred to, as heretofore ordinarily constructed, were liable to get out of order with resultant development of imperfections in the dyeing, or the production of off-shade sections, in the yarn or thread, due to imperfect absorption of the dyestuff throughout the cakes. Moreover, the prior art holders required much time in loading and careful setting-up if the desirable results were to be expected.

The fundamental aim of our present invention is to overcome the above noted disadvantages. This objective is realized in practice as hereinafter more fully disclosed, through provision of a simple holder which is easily and quickly loaded and unloaded; and which is so constructed as to facilitate ready penetration of the yarn packages or cakes by the liquids.

Other objects and attendant advantages of our invention will be, or become, apparent from the following detailed disclosure of a preferred embodiment thereof, considered in connection with the accompanying drawings, while the claims more particularly define the features of novelty over the prior art.

In the drawings:

Fig. 1 is an elevation of a yarn or thread cake holder conveniently embodying our invention.

Fig. 2 is a vertical section taken as indicated by the angled arrows II—II in Fig. 1.

Fig. 3 is a broken plan section taken approximately as indicated by the arrows III—III in Fig. 1.

Figs. 4 and 5 are perspective views of two of the component parts of the holder.

In describing the form of our invention shown in the three sheets of drawings herewith, specific terms will be employed for the sake of clarity, but it is to be understood the scope of said invention is not thereby limited, each such term being intended to embrace all equivalents which perform the same function for an analogous purpose.

Referring more in detail to the drawings, our multiple cake holder comprises a foot-piece or socket connector 6 which is rigidly mounted on, or integrated to, the dye vat 7, said connector having a screw-threaded bore 8 into which the correspondingly threaded lower end 9 of a short tubular axial boss 10 of a circular stop plate 11

2

is engaged. Rising axially from plate 11 is a vertically directed hollow post 12 whereof the upper end is closed as at 13 and provided with a central screw-threaded stud-projection 14.

5 The hollow post 12, it is to be seen from Fig. 2, is preferably integrated at its lower end to the plate 11 by a surrounding weld 15, and is provided with groups of annularly arranged holes 16 centered in zones spaced by a distance substantially equal to the thickness of the yarn packages, and with rings of perforations 17 above and below the holes 16. The post 12 is furthermore provided with diametrically opposed longitudinal grooves 18 having lateral offsets 19 and 20 likewise spaced by a distance substantially equal to the thickness of the yarn packages, said grooves 18 being open at the top, see Figs. 2 and 5.

For placement between packages, we have provided separators designated 21, one of which is 20 shown in Fig. 4 to best advantage. Each such separator consists of two components 22, 22' which are arranged back to back and preferably integrated by an outer surrounding weld 23.

Obviously an inner similar weld may likewise be utilized, if desired. Each component 22, 22' is fashioned from sheet material, such as metal or a durable plastic, and appropriately shaped to include a flat annular part 24 with a peripheral flange or rim 25 and an inner concentric round-merged hub 26 with a ring of holes 27. Particular attention is directed to the formation on the upper component 22 of each separator of a pair of diametrically opposed indentations or lugs 28, Figs. 2 and 4, functional to enter the grooves

35 18 in the post. Upon placement of a separator over a package and impartation of a slight turn thereto, the indentations 28 enter the related groove offset 19 or 20 to lock the separator to the post 12.

40 Seated on and integrated to the circular stop plate 11 by a weld, as at 29, is an element 22' like the lower component of one of the separators 21, said element having in its hub, a ring of holes 27 for registry with the lowermost ring of holes 27 in the hollow post 12. It is also to be noted that we have provided a cover element 22b for the uppermost package in the pile which element is also like one of the components of a separator, and which is integrated by a weld 29 to a plate 30 in turn similar to the stop plate 11, said plate 30 being provided with a central aperture 31 to engage over the stud projection 14 at the top of the post. After placement, plate

45 50 55 30 with the attached element 22b is secured by

a clamp nut 32 screwed onto the projection 14 at the top of post 12.

After common practice in the art, the thread in the package is protected within a fabric wrapper. In the use of the holder, an initial cake or package 33 is impaled over the post 12 and lowered until it seats upon the element 22a attached to stop plate 11, as shown in Figs. 1 and 2. A separator 21 is then applied to the top of the post 12, with incidental entry of its diametral lugs 28 into the longitudinal grooves 18, and then slid downwards onto the package when said indentations will register with the lateral groove offsets 20. Then, by impartation of a slight turn to the separator 21, the lugs 28 thereof are engaged in the respective groove offsets 20 and said separator thereby locked in position. Other cakes and separators are then applied in a similar manner until the holder is filled, and finally the cover plate 39 is placed over the last cake and secured by the nut 32 as in Fig. 2. In the assembled organization, it will be observed that the peripheral flanges of the separators 21 and of the stop and cover elements 22a circumferentially lap the packages, and that their hubs 22b engage partway into the axial hollows of the cake, with the holes in said hubs registering substantially with the rings of 17 and 17' in post 12. As a consequence, and by reason of the illustrated allocation of the grouped rings of holes 16 in the post, the treating liquid is free to flow through and around all of the packages or cakes in the pile so that uniform and thorough penetration of the threads or yarns is assured, while said packages or cakes are effectively held against displacement.

Having thus described our invention, we claim:

1. In a holder for supporting a pile of annular yarn packages or the like, a cylindric post upon which the packages are adapted to be impaled, said post having a longitudinal groove in its outer surface with lateral offsets spaced by a distance corresponding substantially to the thickness of a yarn package; discoid stop element for the first applied package affixed to the post at the bottom; axially-apertured discoid separators for impalement upon the post between packages, each separator having an inwardly projecting radial lug fitting the groove in the post and adapted, when the separator is partially rotated after application over a yarn package, to lock into one of the offsets of said groove; a discoid cover element for engaging downward over the topmost package in the pile; and means for removably securing the cover element to the post.

2. A support for multiple annular yarn packages or the like characterized as in claim 1, wherein each separator is provided with oppositely-directed circumferential flanges to peripherally lap adjacent yarn packages.

3. A holder for multiple annular yarn packages or the like characterized as in claim 1, wherein each separator has oppositely-extending hub portions for engaging part way into the hollows of adjacent yarn packages in the pile; and wherein the inward groove-engaging lug is formed on one of said hub portions.

4. A holder for multiple annular yarn pack-

ages or the like characterized as in claim 1, wherein each separator has oppositely-extending hub portions for engaging part way into the hollows of adjacent yarn packages in the pile; wherein the inward groove-engaging lug is formed on one of said hub portions; wherein the stop element has a hub portion to engage upwardly into the hollow of the lowermost yarn package in the pile, and a circumferential flange to peripherally lap said package; and further including a discoid element similar to the separators for super-imposition upon the topmost package of the pile having a hub portion to engage into the hollow of the last mentioned package.

5. The invention defined in claim 1, wherein each of the separators is formed by two components fashioned from sheet material and weld-integrated back to back, said components being formed respectively with hub portions for engaging into the hollows of adjacent packages in the pile; and wherein the stop and cover elements are each identical with one of the components of a separator.

6. A support for multiple annular yarn packages and the like characterized as in claim 1, wherein each separator is formed by two components fashioned from sheet metal and weld-integrated back to back, said components being formed respectively with hub portions for engaging into the hollows of adjacent packages in the pile; wherein the stop and cover elements are each identical with one of the components of a separator; wherein the hub portions of the separator components and of the stop and the cover elements are respectively provided with annularly arranged holes; and wherein the post is tubular and provided with plural rings of circumferentially arranged perforations centered in the mid transverse planes of the mounted packages, and with other circumferentially arranged perforations in the transverse planes of the holes in the hub portions respectively of the separators, the stop element and the cover element.
